DESIGN FOR A METAL FLOWER BASKET

Roderick M. Koch, Evansville, Ind.

Application September 6, 1934, Serial No. 53,217

Term of patent 7 years

To all whom it may concern:

Be it known that I, Roderick M. Koch, a citizen of the United States of America, residing at Evansville, in the county of Vanderburg and State of Indiana, have invented a new, original, and ornamental Design for Metal Flower Baskets, of which the following is a specification, reference being had to the accompanying drawing, forming part thereof.

The figure is a side elevation in perspective of a metal flower basket, showing my new design.

I claim:

The ornamental design for a metal flower basket, as shown.

RODERICK M. KOCH.
